ELECTRODE HOLDER

Honet A. Jackson, Detroit, Mich.

Application February 4, 1944, Serial No. 521,005

5 Claims. (Cl. 219—8)

1

This invention relates to an electrode holder and more particularly to an electrode holder for arc welding.

This invention contemplates an electrode holder for arc welding which is streamlined and compact to facilitate welding in close quarters.

It is an object of this invention to produce an insulated electrode holder having long lived insulation. This object is achieved by providing the insulation with a protecting metal cover which is insulated from the body and other current conducting parts of the holder.

It is also an object of this invention to produce a holder having a simple, economical and efficient lock for locking the electrode in the holder.

In the drawing:

Fig. 1 is a longitudinal section through my electrode holder showing the parts in released position.

Fig. 2 is a fragmentary longitudinal section along the line 2—2 of Fig. 6 through my holder showing the electrode locked in the holder.

Figs. 3, 4 and 5 are sections along the lines 3—3, 4—4 and 5—5 of Fig. 2.

Fig. 6 is an elevation of my electrode holder. From the drawing it will be observed that the holder is shaped like a torpedo. The holder comprises the following parts: a head 1, an insulating cover 2 for the head, an electrode locking plunger 3 mounted in bore 4 in the head, a metal protecting shield 5 for the insulating cover 2, an insulating handle 6 mounted on a metal adapter 7 which has a threaded fit with the head as at 8, a cable 9 secured in the end of the adapter 7 and in electrically conducting relation therewith by the set screws 10. The electrode is designated 11.

The head 1, plunger 3, adapter 7 and cable 9 can be made from any of the well-known metals or alloys having high electrical conductivity, such as copper, aluminum, and their alloys.

Head 1 is streamlined and shaped like the head of a torpedo. The insulating cover 2 completely surrounds head 1 and can be made from electrical and heat insulating materials preferably having low heat conducting properties, capable of withstanding high temperatures and also having high strength. The insulating cover should be capable of withstanding high impact because the electrode holder is frequently dropped by the operator and in many cases may even be used as a hammer or subjected to other abuses wherein the insulation is subjected to high impact. Insulating cover 2 can be made from high temperature thermosetting plastics, such as Bakelite. Preferably canvas

reenforcement is molded within the Bakelite cover.

Insulating cover 2 is provided with a metal shield or sheath 5 which surrounds the insulating cover at the head end of the holder. Shield 5 is preferably made of thin sheet brass or aluminum and serves to protect insulation 2 against the heat radiated from the arc during welding and also serves to protect the insulation against damage in case the head of the holder is struck or strikes against another object such as might occur when the holder is dropped. Insulating cover 2 is preferably molded in the metal nose or shield 5 and has a skirt portion 40 overlapping handle 6 and which serves as a hand-grip for turning the head 1 to lock the electrode in the head or release the same therefrom. The nose portion and hand-grip portion of the insulating cover 2 preferably are molded as one integral piece or unit. Shield 5 is circumferentially knurled as at 41 and insulation 2 is molded over the knurled portion as at 42 so as to lock the insulating cover to the shield 5.

The metal sheath 5 is provided with an opening 12 surrounding an opening 13 in insulating cover 2 through which the electrode is adapted to be passed into socket 14 of head 1. The insulation 2 is preferably molded in cover 5 and fills the opening 12 flush with the outside surface of sheath 5. Insulating cover 2 and sheath 5 are retained on head 1 by a locking pin 15 which passes through openings provided in head 1, insulation 2 and sheath 5. Pin 15 is arranged to be driven out of the head and insulation members to permit removal of the insulating cover 2 from the head 1. Pin 15 is preferably made from canvas reenforced molded plastic such as Bakelite.

Handle 6 is preferably tubular and retained on the adapter 7 by means of a tapered pin 16 driven into opening 17 in adapter 7 and into openings 18 in handle 6. Tapered pin 16 prevents handle 6 from slipping on adapter 7 and since it is made from insulating material such as molded Bakelite or Bakelite reinforced with canvas or asbestos fibre, pin 16 prevents arcing. Pin 16 can be removed by driving the same out of openings 17 and 18.

Adapter 7 is provided with a bore 19 threaded as at 8 and is arranged to have a screw fit on the threaded end of head 1. This screw fit of the handle adapter 7 on head 1 is utilized for moving plunger 3 into locking engagement with the electrode 11 and also for releasing the same. Plunger 3 is provided with a ball bearing 20 at each end. Each ball bearing is retained in its socket 21 by

peening over the surrounding edge of the socket as at 22. The ball bearing 29 is free to rotate in its socket 21 and thus presents a different surface for contact or locking engagement with the electrode 11 each time the electrode is replaced. This distributes the wear fairly uniformly over the surface of locking bearing 21. When one ball bearing shows appreciable wear the plunger 3 is removed from the head and turned end for end, thus presenting the other ball bearing for locking engagement with the electrode.

The plunger 3 has a reduced portion 23 intermediate its ends. A locking pin 24 has a friction fit in opposed openings in the head 1 and passes through the recess or clearance provided between the ends of the plunger by the reduced central portion 23. Thus plunger 3 is free to move longitudinally in bore 25 of head 1 but cannot fall out when head 1 is disconnected from the handle 6, 7.

When it is desired to replace plunger 3, handle 6, 7 is screwed off the end of head 1, pin 24 is driven out or removed from the head, and this permits plunger 3 to drop out of the head. If for any reason the plunger should stick in the head, a small rod can be passed through opening 26 in the head end of the holder and the plunger driven out. Insulation 2 and the metal cover 5 can be removed from the head by first removing the locking pin 15 which permits the insulation and metal cover to be slid off the head.

In operation the end of the electrode 11 is slid into socket 14 and handle 6 is turned from the position shown in Fig. 1 whereupon the bottom 21 of bore 19 in adapter 7 engages the right hand ball 20 to move the plunger forward toward the electrode. This brings left hand ball 29 into a tight locking engagement with the end of the electrode. The current is principally carried to the electrode from the cable 9 through adapter 7 and head 1, although a minor flow of current will pass through plunger 3.

It should be noted that the head end of the electrode holder has an outline in longitudinal section which is substantially a parabola. Making the head end of the holder a parabola in longitudinal section gives the holder a compactness so that it is capable of working in much closer quarters than other types of holders now on the market.

The pitch of threads 8 is such that a quarter turn of handle 6, 7 is all that is necessary to lock the plunger against, or release it from, the weld rod 11. This facilitates loading and unloading of the holder. To remove handle 6 from adapter 7, pin 16 is first driven out of openings 17, 18 whereupon the handle can be slid off adapter 7. The use of pin 24 is optional and the same can be omitted if desired.

Head 1 is preferably provided with a plurality of longitudinal grooves 50 which provide air spaces between head 1 and the insulating cover 2 to aid in cooling head 1.

I claim:

1. An electrode holder comprising in combination an electrically conducting head having a socket therein adapted to receive the end of an electrode, said head having a longitudinal bore communicating with said socket, a plunger slideable in said bore, ball bearings journaled in the opposite ends of said plunger whereby said ball

bearings and plunger are removable as a unit from said head, and means co-acting with said head and the ball bearing in one end of said plunger whereby the ball bearing in the opposite end of the plunger is forced into locking engagement with an electrode in said socket.

2. An electrode holder comprising in combination an electrically conducting head having a socket therein adapted to receive the end of an electrode, said head having a longitudinal bore communicating with said socket, a plunger slideable in said bore, ball bearings journaled in the opposite ends of said plunger whereby said ball bearings and plunger are removable as a unit from said head, a handle independent of said plunger having a screw fit on the end of said head and contacting one of said ball bearings for forcing the other ball bearing into locking interengagement with an electrode in said socket.

3. An electrode holder comprising in combination an electrically conducting head, an insulating cover surrounding said head, said head having a socket adapted to receive the end of an electrode, said insulating cover having an opening adjacent said socket through which the end of the electrode is passed into said socket, cooperating openings in said head and insulation, and a pin of insulating material passing through said openings for locking the insulating cover on said head.

4. An electrode holder comprising in combination an electrically conducting head, an insulating cover surrounding said head, said head having a socket adapted to receive the end of an electrode, said insulating cover having an opening adjacent said socket through which the end of the electrode is passed into said socket, and a metal cover surrounding said insulating cover and insulated from said head, said metal cover also having an opening adjacent the aforementioned opening in the insulating cover for said electrode, said metal cover serving to reflect heat radiating from the welding arc and to protect the insulating cover against damage, and cooperating openings in said head and insulating cover, and a pin of insulating material in said openings for locking the said head, insulating cover and metal cover together as a unit.

5. An electrode holder comprising in combination an electrically conducting head, an electrically conducting adapter having a threaded connection with said head, an insulating handle covering said adapter, an insulating cover surrounding said head and having a skirt portion which overlaps one end of the insulating handle, said head having a socket adapted to receive an end of an electrode, said insulating cover having an opening adjacent said socket through which the end of the electrode is passed into said socket, and means of electrically non-conducting material for locking said insulating cover to said head, and a plunger mounted in said head having one end arranged to contact said adapter and the other end to project into said socket whereby relative rotation between the hand-grip portion of said insulating cover and the handle effects longitudinal movement of said plunger and projects the said other end of the plunger into said socket to lock an electrode therein.
